(57) **CLAIM**

The ornamental design for the "rifle sighting stand," as shown and described.

DESCRIPTION

FIG. 1 is a perspective view of a rifle sighting stand showing my design;

FIG. 2 is a top elevational view thereof;

FIG. 3 is a bottom plain view thereof;

FIG. 4 is a right-side elevational view thereof;

FIG. 5 is a left side elevational view thereof;

FIG. 6 is a rear elevational view thereof;

FIG. 7 is a front elevational view thereof; and,

FIG. 8 is a side elevational view thereof. The broken lines are for illustrative purposes only, and form no part of the claimed design.
